UNITED STATES PATENT OFFICE.

CYRUS C. BULTMAN, OF CLEVELAND, OHIO, ASSIGNOR TO THE BRUNSWICK-BALKE-COLLENDER COMPANY, OF CHICAGO, ILLINOIS, A CORPORATION OF DELAWARE.

SURFACING-MACHINE FOR BOWLING-ALLEYS.

1,319,041.

Specification of Letters Patent. Patented Oct. 21, 1919.

Application filed July 2, 1917. Serial No. 178,073.

To all whom it may concern:

Be it known that I, CYRUS C. BULTMAN, a citizen of the United States, residing at Cleveland, in the county of Cuyahoga and State of Ohio, have invented certain new and useful Improvements in Surfacing-Machines for Bowling-Alleys, of which the following is a specification.

The primary object of my invention is the provision of a self propelled and easily controllable machine carrying means actuated by driving mechanism supported on the machine for abrading the surface of an alley bed to bring it to a predetermined level and for subsequently polishing the bed.

Further objects and advantages of my invention reside in the provision of means for adjusting the surfacing and polishing devices relatively to the alley bed, of means for removing the debris as formed, of means whereby the machine may be taken down for transportation and in the various combinations of elements whereby the structure and operation of the machine is simplified as will be better understood by reference to the following specification when read in connection with the accompanying drawing, illustrating the preferred embodiment thereof, in which—

30 Figure 1 is a plan view of the machine with the hoods removed;

Fig. 2 is a side elevation of the machine;

Fig. 3 is a longitudinal section through the machine;

35 Fig. 4 is a front elevation of the machine;

Fig. 5 is a section on the line 5—5 of Fig. 3;

Fig. 6 is a section through the abrading drum and adjusting means therefor;

40 Fig. 7 is a section on the line 7—7 of Fig. 6;

Fig. 8 is a section on the line 8—8 of Fig. 6;

Fig. 9 is a section on the line 9—9 of Fig. 2;

45 Fig. 10 is a section on the line 10—10 of Fig. 9;

Fig. 11 is a detail in section illustrating the actuating eccentric for reciprocating the abrading drum, and

50 Fig. 12 is a detail in section illustrating the connection of the polisher to its operating mechanism.

Referring to the drawing, 5 indicates a frame carrying a platform 6 and supported on forward and rear wheels 7 and 8, respectively, the latter being the driving wheels and actuated from the motor 9 mounted on the platform 6 in the manner presently to be described.

Supported on the frame 5 near its forward end within a housing 10 is a transversely extending shaft 11 having a sprocket 12 fixed thereto which is driven by a chain 13 from a sprocket 14 on the shaft 15 of the motor 9. The shaft 11 is provided with a worm 16 meshing with a worm gear 17 on a shaft 18 extending longitudinally of the frame 5. A worm 19 on the shaft 18 meshes with a worm gear 20 keyed to a pinion 21 (Fig. 9) which is loose on the transverse shaft 22 to which the driving wheels 8 are secured. The pinion 21 meshes with a gear 22' (Fig. 10) mounted on a jack shaft 23 and carrying a pinion 24 which meshes with a gear 25 loose on the shaft 22. The gear 25 is provided with clutch teeth 26 and a corresponding clutch element 27 is splined to the shaft 22. A lever 28 is pivotally mounted at 29 on the frame and is adapted to throw the clutch element 27 into mesh with the clutch teeth 26 to connect the shaft 22 to the driving mechanism and thus operate the driving wheels 8 at reduced speed. An operating handle 29 is connected to the lever 28 so that the clutch may be thrown from either side of the machine. Scrapers 30 are mounted in suitable brackets 31 on the frame 5 in front of the driving wheels 8 to remove debris from the path of the wheels. Brushes 32 are similarly mounted on the frame and engage the periphery of the wheels 8 to remove any debris which might otherwise accumulate thereon.

Secured to the frame 5 adjacent the ends of the shaft 11 are housings 33 removably secured by bolts 33' to the frame 5 (Fig. 5) which support short shafts 34 having clutch teeth 35 at their inner ends co-operating with corresponding clutch teeth 36' on the outer ends of the shaft 11. Rigid side members 36 are pivotally mounted adjacent the ends of the shafts 34 and extend forwardly from the frame to support the transverse shaft 37 which is mounted at its ends in suitable bearings on the members 36 and supports

the abrading roll 38, the latter having an abrading surface consisting preferably of sandpaper secured to its surface. The shaft 37 is driven from the shafts 34 by chains 39 5 engaging sprockets 40 and 41 on the shafts 34 and 37, respectively. The outer ends of the members 36 are connected by a rod 42 on which is supported a bracket 43 carrying a spirit level 44. The rod 42 is parallel to 10 the shaft 37 and consequently the spirit level 44 indicates when the abrading surface of the drum 38 is level.

The shaft 37 is connected at one end to a lever 45 (Fig. 1) pivoted at 46 on one 15 of the members 36 and in turn connected by a rod 47 to a lever 48 pivoted at 49 on the housing 10. A rod 50 connects the lever 48 to an eccentric collar 51 (Fig. 11) mounted on the eccentric 52 which is fast to the shaft 20 18. Thus as the shaft 18 rotates the shaft 37 is reciprocated, moving the drum 38 slightly from side to side and preventing scoring of the alley bed should the abrading surface of the drum be slightly impinging 25 feet.

The outer ends of the members 36 are pivotally connected to and supported on frames 53 (Figs. 6 and 8) to which shoes 54 are adjustably connected. The shoes 54 are provided with rollers 55 for engagement with the alley bed. The shoes 54 are provided with upwardly extending screws 56 slidably mounted within suitable openings in the frames 53. Worm gears 57 are threadedly 30 mounted on the screws 56 and bear at either side on the interior walls of the frame as clearly shown in Fig. 8. Shafts 58 carrying hand wheels 59 are rotatably mounted in the frames 53 and are provided with worms 35 60 meshing with the worm gears 57. By operating the hand wheels 59 the outer ends of either of the members 36 may be raised or lowered, causing a corresponding movement of the abrading surface of the drum 38 relative to the alley bed. Thus the abrading surface may be maintained level as indicated by the spirit level 44.

As the machine approaches the end of the alley bed the shoes 54 pass out over the pit 50 and in order that the end may be properly surfaced it is necessary to provide auxiliary supporting means for the members 36. For this purpose I provide a transverse member 55 61 (Figs. 1 and 6) connecting the members 36. Adjacent its ends the member 61 is supported in boxes 62 slidably mounted in U-shaped members 63 carrying rollers 64 at the extremities of their arms for engagement with the alley bed. The boxes 62 are 50 connected to the ends of screws 65 threadedly mounted in the U-shaped member 63 and provided with hand wheels 66. By rotating the hand wheels 66 the ends of the member 61 and consequently the members 36 65 may be vertically adjusted relatively to the

alley bed to vary the relation of the abrading surface of the drum 38 thereto and maintain the surface level.

It is frequently necessary to lift the abrading drum entirely from the surface of the 70 alley bed and particularly while the polishing mechanism, presently to be described, is in operation. This is accomplished in my machine by mounting a transverse shaft 67 (Figs. 6 and 7) on the frame 5 and mounting 75 arms 68 thereon having bifurcated ends embracing the member 61. A sector 69 is secured to the shaft 67 and is provided at its upper end with teeth meshing with a worm 70 on a shaft 71 journaled in a bracket 72 80 on the frame 5. A gear 73 on the shaft 71 meshes with a pinion 74 on a shaft 75 mounted in an arm of the bracket 72. A hand wheel 76 is secured to the shaft 75 and upon rotation of the latter the arms 68 may 85 be raised or lowered to swing the members 36 toward and away from the alley bed. Thus the drum 38 may be quickly raised when necessary from engagement with the 90 alley bed.

At the rear of the machine a frame 77 (Fig. 3) is removably secured by suitable bolts to the frame 5 and carries at its outer end a vertical shaft 78 adapted to be raised and lowered by means of a lever 79 pivotally 95 mounted at 80 on a bracket 81 secured to the frame 77. One arm of the lever 79 engages a collar 82 on the upper end of the shaft 78 and the other a collar 83 embracing a screw 84 projecting upwardly from 100 the frame 77. The collar 83 is provided with a hand wheel 85 and by operating the hand wheel the collar 83 may be moved vertically on its screw 84 to control the shaft 78. A housing 86 forming part of the frame 77 105 supports a sleeve 87 which surrounds and is splined to the shaft 78. The sleeve 87 is provided at its lower end with a bevel pinion 88 meshing with a bevel gear 89 fast to the shaft 90 which is detachably connected 110 at 91 to the shaft 18.

The lower end of the shaft 78 is provided with a head 92 (Fig. 12) having depending ears 93 in which a block 94 is pivotally hung. A polishing head 95 is pivotally supported 115 on the block 94, the construction being such that the polishing head has a universal movement with respect to the shaft 78 and may consequently follow the surface of the alley bed regardless of the relative angularity of 120 the shaft 78 with respect thereto. The polishing head 95 is surfaced with any suitable material adapted to smooth and polish the surface which has been previously reduced to a level by the abrading drum 38.

The abrading drum 38 and polishing mechanism just described are surrounded by hoods 96 and 97, respectively, of sheet metal (Figs. 2 and 3). A suction blower 98 is mounted on the frame 5 and is driven 130

from a sprocket 99 (Fig. 5) on the shaft 11 by a chain 100 (Fig. 1) which actuates a corresponding sprocket on the shaft 101 of the blower. The inlet to the blower is connected by a pipe 102 (Fig. 2) to the hood 96 surrounding the abrading drum 38. The outlet side of the blower is connected by a pipe 103 to a dust bag 104 supported on the frame 5. When the polishing mechanism is 5 in operation the pipe 102 is removed and a pipe 105, indicated in Fig. 2, connects the hood 97 to the inlet side of the blower. It is understood that it is my intention to operate the abrading drum 38 and the polishing 10 mechanism separately and consequently permanent connections between both the hoods 96 and 97 and the blower are not essential. However, such a connection may be provided and overcomes the inconvenience of changing 15 the pipes 102 and 105 in accordance with the operation about to be carried out. The members 36 are provided at their extremities with laterally projecting arms 106 carrying rollers 107 adapted to engage the sides of the 20 alley and similarly the rear end of the frame 5 is provided with arms 108 carrying rollers 109. The engagement of the rollers 107 and 109 with the sides of the alley insure proper alignment of the machine and assists materially in the successful operation thereof. 25

From the foregoing it will be readily understood that I have perfected a compact and easily operable machine for leveling and polishing alley beds. The structure is particularly designed to permit various parts thereof to be readily removed so that the machine may be taken down and transported from place to place as needed. The mechanism is so controlled that the worn surface 40 of an alley bed may be quickly reduced to a level with a great saving of labor and expense as compared with the usual manual treatment of such surfaces.

It will be apparent that various changes 45 may be made in the form, construction and arrangement of the parts without departing from the spirit and scope of the invention or sacrificing any of its material advantages, the form hereinbefore described being merely a preferred embodiment thereof.

I claim:

1. In a machine of the character described, the combination of a movable supporting carriage, members pivotally supported thereon and extending forwardly therefrom, an abrading drum supported on said members, a driving shaft in sections connected end to end, and driving connections between said drum and shaft, said sections being separable whereby said connection is readily broken to permit removal of said members from the machine.

2. In a machine of the character described, the combination of a movable supporting carriage, members pivotally sup-

ported thereon and extending forwardly therefrom, a drum supported on said members, a driving shaft having separate end sections, a clutch connection between said shaft and each of said end sections, and driving connections between said drum and end sections. 70

3. In a machine of the character described, the combination of a movable supporting carriage, a transverse driving shaft 75 having separable end sections, members pivotally supported on said sections and extending forwardly therefrom, an abrading drum journaled in said members, a driving connection between said drum and sections, 80 means for adjustably supporting the forward extremities of said members, and auxiliary supporting means for said members intermediate said drum and shaft.

4. In a machine of the character described, the combination of a frame, members pivotally mounted in both sides of said frame and projecting forwardly therefrom, an abrading drum journaled in said members, means for rotating said drum, and 90 means for bodily lifting said drum and members including a transverse connecting member, a shaft on said frame, bifurcated means on said shaft engaging said connecting member, and means for oscillating said 95 shaft.

5. In a machine of the character described, the combination of a frame, members pivotally mounted in both sides of said frame and projecting forwardly therefrom, 100 an abrading drum journaled in said members, means for rotating said drum, and means for bodily lifting said drum and members including a transverse connecting member, a shaft on said frame, bifurcated means 105 on said shaft engaging said connecting member, and means for oscillating said shaft, including a toothed sector connected to said shaft, and means for actuating said sector. 110

6. In a machine of the character described, the combination of a frame, members pivotally mounted in both sides of said frame and projecting forwardly therefrom, an abrading drum journaled in said members, means for rotating said drum, and means for bodily lifting said drum and members including a transverse connecting member, a shaft on said frame, bifurcated means on said shaft engaging said connecting member, and means for oscillating said shaft, including a toothed sector connected to said shaft, a hand wheel mounted on said frame and operative connections between 115 said hand wheel and sector. 120

7. In a machine of the character described, the combination of a frame, members pivotally mounted in both sides of said frame and projecting forwardly therefrom, an abrading drum journaled in said members, 130

means for rotating said drum, and means for bodily lifting said drum and members including a transverse connecting member, a shaft on said frame, bifurcated means on said shaft engaging said connecting member, means for oscillating said shaft, and means for adjusting the angular relation of the surface of said drum to the surface to be abraded.

10 8. In a machine of the character described, the combination of a frame, members pivotally mounted on both sides of said frame and projecting forwardly therefrom, an abrading drum journaled in said members, 15 means for rotating said drum, and means for adjusting the angular relation of the surface of said drum to the surface to be abraded, including shoes mounted on the forward extremities of said members and 20 having rollers to engage the latter surface, and means for adjusting said shoes relative to said members.

9. In a machine of the character described, the combination of a frame, members pivotally mounted on both sides of said frame and projecting forwardly therefrom, an abrading drum journaled in said members, means for rotating said drum, and means for adjusting the angular relation of the 25 surface of said drum to the surface to be abraded, including frames pivotally connected to the extremities of said members, shoes having screws projecting into said frames, means within said frames thread- 30 edly engaging said screws, and manually 35 operable means for actuating the latter means.

10. In a machine of the character described, the combination of a movable sup- 40 porting carriage, an abrading drum supported on said carriage, polishing means supported on said carriage, hoods surrounding said abrading drum and polishing means, a suction blower supported on said 45 carriage, a dust bag connected to the outlet of said blower, and means for connecting either of said hoods to the inlet of said blower.

11. In a machine of the character de- 50 scribed, the combination of a movable sup- porting carriage, an abrading drum sup- ported on said carriage, polishing means supported on said carriage, hoods surrounding said abrading drum and polishing 55 means, a suction blower supported on said carriage, a dust bag connected to the outlet of said blower, means for connecting either of said hoods to the inlet of said blower,

and means for raising said drum from the surface to be treated while said polishing 60 means is in operation.

12. In a machine of the character de- 65 scribed, the combination of a frame, a driv- ing shaft mounted in said frame, said shaft being in separable sections connected end to end, members pivotally mounted on the outer sections of said shaft at both sides of said frame and projecting forwardly there- 70 from, an abrading drum journaled in said members, means for rotating said drum from said shaft, and means for adjusting the angular relation of the surface of said drum to the surface to be abraded, includ- 75 ing shoes mounted on the forward extremi- ties of said members and having rollers to engage the latter surface, and means for adjusting said shoes relatively to said mem- bers.

13. In a machine of the character de- 80 scribed, the combination of a frame, a driv- ing shaft in said frame, said shaft being in separable sections connected end to end, members pivotally mounted at both sides of said frame and projecting forwardly there- 85 from, an abrading drum journaled in said members, means for rotating said drum from said shaft, and means for adjusting the angular relation of the surface of said drum to the surface to be abraded, includ- 90 ing shoes mounted on the forward extremi- ties of said members, and means for adjust- 95 ing said shoes relatively to said members.

14. In a machine of the character de- 95 scribed, the combination of a frame, a driv- ing shaft in said frame, said shaft comprising a centrally disposed rigid section and separable end sections, members pivotally mounted at both sides of said frame and pro- 100 jecting forwardly therefrom, an abrading drum journaled in said members, driving connections between said separable sections and the drum for rotating the latter, power means for rotating said driving shaft, a worm on said central section, a shaft sup- 105 ported in the frame and extending longitudinally of the machine, a worm gear on said shaft meshing with said worm, driving wheels, a shaft carrying said wheels and sup- ported in the frame, a worm gear on said last mentioned shaft, and a worm on said longi- 110 tudinal shaft meshing with said last mentioned worm gear.
